CLAIM

The ornamental design for a adjustable fishing rod holder, as shown and described.

DESCRIPTION

FIG. 1 is a perspective view of the adjustable fishing rod holder illustrating my new design;

FIG. 2 is a side elevational view of the adjustable fishing rod holder of FIG. 1, the other side having the same appearance;

FIG. 3 is a top plan view thereof;

FIG. 4 is a front end elevational view thereof;

FIG. 5 is a rear end elevational view thereof; and,

FIG. 6 is a bottom plan view thereof.
